DROP HAMMER

Forrest E. Smith, 151 Point Circle,
Jupiter Tequesta, Fla. 33458
Filed Aug. 9, 1966, Ser. No. 571,235
14 Claims. (Cl. 241—291)

The present invention relates generally to an improved massive body or weight of the type utilized for breaking rocks or other materials and which may also be utilized in various other types of demolition operations. In its principal aspect the invention is concerned with improved heavy bodies of the foregoing type characterized by greater toughness, hardness, strength and durability to withstand extreme impact and abrasion in use and yet may also include provision to compensate for weight loss that occurs over the useful life thereof.

It has been common practice in quarrying operations or the like to utilize a very heavy inertia body to break large rocks or other materials into smaller pieces thereby rendering the material more suitable for subsequent handling. When rock is dynamited loose in a quarry, frequently the size of the rock obtained is still too large to be crushed by rotary or other available types of mechanical crushers. Heavy bodies, commonly referred to as drop hammers, are utilized to further break the rock to a more useful size by lifting the hammer to a required height with a crane and allowing the hammer to freely drop on the oversized rock to be broken.

In order to break large rock pieces into acceptable sizes, the hammer must be quite heavy, especially when working with granite or other hard rock. However, the weight of the hammer should not be too excessive for the equipment which is to handle the hammer. The hammer must be of a size which is capable of being hoisted by a crane several hundred times a day and yet of a size permitting efficient breaking of the rocks. In actual practice, it has been customary to start with a hammer having a weight closely approaching the maximum continuous operating capability of the hoisting equipment, e.g. when using a crane rated at approximately 1½ yard size with a boom length of 50 to 60 feet, the hammer weighs approximately 10,000 pounds, and the hammer is discarded when it is worn down by repeated impacts with rock at the point when it is no longer heavy enough to be effective when dropped from a practical height. With the exemplary 10,000 pound hammer, it is customary to discard the hammer when the weight is reduced to around 5,000 or 6,000 pounds.

In view of the obvious economic loss incurred by having to discard worn down hammers, often at a very low salvage value, numerous different approaches have heretofore been utilized to avoid having to throw away such a large portion of the original drop body. For example, one approach has involved the use of a discardable or replaceable shoe type attachable member. This type of construction is multi-part and includes a relatively heavy drop body and a replaceable shoe type wearing portion which is attached to the drop body by a relatively thin stem. While the shoe portion can be relatively easy to replace, both the shoe and the connecting stem are easily deformed and broken in normal operation and in many cases, this occurs even after only a few hours usage. Consequently, such drop hammers require continual shoe replacement and therefore do not solve the problem of economic loss sustained through wear of the hammer.

Other approaches have been to seek metals or methods of treating the metals to possess a much required resistance to impact wear and abrasion to which such hammers are subjected. Certain metals such as austenitic manganese (Hadfield) steels which do possess the neces-

2

sary qualities of toughness, hardness, strength and durability have been completely overlooked or intentionally discarded by the industry. Even though it has been found to be particularly useful in mining equipment for ore crushing, digger teeth and the like, the industry has heretofore considered this material not satisfactory for use in drop hammers and certain limitations to the use of this steel have been set. Due to the high coefficient of thermal expansion (about 1½ times that of pure iron) and the low heat conductivity (about ¼ that of carbon steel) there is a great difference in the cooling rates of the exterior and interior of a manganese steel piece when subjected to the drastic heat treatment required to form articles of this material. To dissolve the carbide in the austenite, manganese steel must be heated to over 1800° F. and quenched in cold water, however, the "lag" of the inside of the metal in cooling coupled with the high coefficient of expansion, sets up stresses of such magnitude that large sections of manganese steel of thicknesses greater than the effective penetration depth of the coolant cannot be quenched without producing cracks which generally start within the body and work toward the surface.

Accordingly, it is a general aim of the present invention to provide an improved drop hammer which overcomes all of the foregoing disadvantages and which is characterized by its ability to permit substantially longer periods of usage than heretofore possible, yet wherein this result is achieved without effecting the operating efficiency or causing substantial economic loss.

A related object of the invention is the provision of an improved drop hammer adapted to maintain a relatively constant weight for maintaining the most effective operating efficiency when used in material breaking operations. In this connection it is an object of the present invention to provide an improved drop hammer wherein when weight loss occurs through wear, such loss can be readily compensated by adding a low cost material directly to the body portion in order to retain the most effective operating efficiency.

In another of its important aspects, it is an object of the invention to provide an improved drop hammer which can be constructed of a tough, low wearing coefficient alloy steel capable of withstanding the impact and abrasion to which such drop hammers are subjected to a much greater extent and for a longer period of time than heretofore possible. Thus, it is an object of the present invention to provide a drop hammer which may be made of austenitic manganese steel or the like.

It is yet another object related to the foregoing to provide a drop hammer cast from manganese steel or the like wherein provision is made to facilitate proper heat treatment of all portions of the metal, yet permitting a drop body of suitable weight and mass to be formed enabling the hammer to be used to break oversized rocks and the like.

It is finally an object to provide a drop hammer formed of cast manganese steel that may be effectively heat treated yet avoids internal strains and fissures or cracks which would cause a weakening of such structures.

Other objects and advantages of the invention will become apparent upon reading the attached detailed description and upon reference to the drawings in which:

FIGURE 1 is an exemplary illustration showing a drop hammer crane incorporating the features of the present invention;

FIG. 2 is an enlarged elevation view, partly in section of the drop hammer shown in FIG. 1;

FIG. 3 is a fragmentary, enlarged front side view of the drop hammer in FIG. 2;

FIG. 4 is a top view of the drop hammer in FIG. 3;

FIG. 5 is an elevation view, partly in section, similar to FIG. 2 but here depicting a slightly modified form of

drop hammer also embodying the features of the present invention;

FIG. 6 is a transverse section taken substantially along the line 6—6 in FIG. 5;

FIG. 7 is a fragmentary, front side view of the drop hammer in FIG. 5; and

FIG. 8 is an elevation view partly in section of still another slightly modified form of the present invention.

While the invention is susceptible of various modifications and alternative forms, specific embodiments thereof have been shown by way of example in the drawings and will herein be described in detail. It should be understood, however, that it is not intended to limit the invention to the particular forms disclosed, but, on the contrary, the intention is to cover all modifications, equivalents and alternatives falling within the spirit and scope of the invention as expressed in the appended claims.

Referring now to the drawings, and particularly to FIGS. 1 and 2, there is illustrated an exemplary drop hammer, generally indicated at 10, which is particularly suited for being lifted to a required height by a traveling crane 12 and allowed to freely drop on a rock 14 or the like in order to break the rock into smaller pieces more suitable for subsequent handling. As best shown in FIG. 2, the exemplary drop hammer 10 includes a heavy drop body 16 which is generally cylindrical in shape. It will be understood, however, that the body 16 may be of any suitable size or shape depending upon the use to which it is put and may, for example, be spherical in its general outer configuration while circular or polygonal in cross-section.

For the purpose of connecting the drop hammer to the cable 18 of crane 12, there is provided a suitable hitch member 20 formed at the upper end 21 of body 16. The hitch member 20 includes aligned openings 22 through webs 23 projecting from the body 16. The cable 18 may be attached to member 22 by any connection loop or hitching means.

In accordance with one of the important aspects of the present invention, the drop body 16 is constructed of manganese steel wherein provision is made to insure that proper heat treatment of all portions of the metal can be effected. Thus, a drop body in accordance with the present invention can be formed of any suitable weight and mass and is capable of withstanding the impact and abrasion to which such drop hammers are subjected to a much greater extent and for a longer period of time. To this end, referring to the exemplary drop hammer construction shown in FIG. 2, the body 16 is formed of a plurality of sections or walls 24 with the walls having a maximum allowable thickness T not exceeding the effective penetrating depth of a quenching liquid or coolant when heat treating the walls.

In the case of manganese steel, heat treatment is effected by heating above 1800° F. and then plunging into a coolant such as cold water or the like which gels the grain structure of the metal and results in a steel wholly austenitic in nature and extremely durable and strong. In order to properly heat treat manganese steel avoiding internal strains and fissures or cracks, no portion of the metal between cooling surfaces should be greater than approximately 2½ inches from a cooling surface, and the thickness of heat treatable sections is preferably not over approximately 4½ inches thick.

In the exemplary form of drop hammer shown in FIG. 2, the body is cast from manganese steel and to facilitate rapid cooling of the body after heat treatment, thereby tempering and toughening the metal, a plurality of passages 28 are provided for circulation of a quenching fluid through the body thus positively rendering every portion of the body walls 24 tough and homogeneous. In this form of the present invention, FIG. 4, the body walls 24 are in the form of a plurality of concentric spaced tubular sections with a plurality of radially extending spokes or members 32 interconnecting tubular sections to define the passages 28 in the body. Both the tubular sections 24 and

the members 32 are uniform in section and their respective thicknesses do not exceed the maximum penetration depth of the quenching liquid circulated through the passages 28 and about the outer surface of the body. In keeping with this form of the invention shown in FIG. 4, the passages 28 are dimensioned so as to permit sufficient flow of quenching liquid therethrough. While the maximum thickness of the tubular sections 24 and interconnecting members 32 for effecting adequate heat treatment of the metal is approximately 5 inches, it is preferred that the members be made within the range of approximately 3½ to 4½ inches so that there is no portion of metal that would be beyond the penetrating reach of coolant flowing about the surface of the body and through the passages when it is quenched.

Upon plunging the heated body into a volume of liquid coolant, it will be noted that liquid will flow upward through the passages 28 due to pressure of displacement by the massive body and the outside surface of the body will be surrounded by coolant so that proper heat treatment will be obtained for every portion of metal forming the body.

It will be appreciated by those skilled in the art, that while only three tubular sections 24 interconnected by members 32 are shown, that this number as well as the length of the body may be varied within relatively wide limits depending upon the total weight of the drop hammer that is desired.

Referring now to FIGS. 5, 6, and 7, a slightly modified form of drop hammer, generally indicated at 40, has been depicted. In this instance, and in accordance with another important aspect of the present invention, provision is made on the one hand to increase the weight of the body or on the other hand, to compensate for weight loss upon use thereby enabling the body portion to be used for greater lengths of time without any appreciable loss of operating efficiency. To this end, a cavity 42 is provided in the upper end portion 21a of the body portion 40 while the lower end portion 43 is substantially the same construction shown in the previous embodiment. In this instance, molten lead or any other suitable mass of relatively heavy material can be poured into the cavity 42 through openings 44 between web members 46 at the top of the body. Cylindrical member 47 supported by webs 46 serves as means to attach the cable to the drop hammer.

One of the advantages of the present form of the invention is that the provision of the cavity 42 for receiving a relatively heavy mass of material enables the use of a standardized, basic drop hammer wherein the weight can be increased very simply and economically should the user desire a heavier drop hammer for more rugged applications. A further advantage of the invention is that as the lower portion 43 of the drop hammer is worn away additional mass of relatively heavy material can be added in cavity 42 maintaining the operating efficiency without having to throw away a large portion of the original body as was necessary with previous types of drop hammers.

For the purpose of preventing molten lead or other relatively heavy material added in cavity 42 from flowing downwardly through the passages 28a plugs 48 are provided which may be formed of metal, refractory materials or other composite materials having a melting or flash point higher than that of the molten lead or other material being poured into the cavity. Other manners of covering the passage openings may alternatively be utilized without departing from the present invention.

In keeping with the foregoing important aspect of the present invention, referring to FIG. 8, there is shown still a further modified form of the present invention wherein the drop hammer body portion 40a still includes the cavity 42a for receiving a relatively heavy mass of material, however, in this instance the lower portion 43a of the drop hammer is constructed of any suitable tough, low wearing coefficient steel or alloy capable of withstanding

the impact and abrasion in use. Since the drop hammer includes the cavity 42a, lead or other heavy material may be added to compensate for weight loss due to wearing of the lower portion, thus extending the life of the hammer considerably. In either case, that is, whether at least the lower portion is formed of austenitic manganese steels or other suitable wear resistant and durable metals, the inclusion of the fillable cavity enables the user to extend the life of the drop hammer without sacrificing efficiency or to easily change the weight of a single drop hammer for use with differing crane and boom capacities without maintaining a stock of different sized drop hammers.

I claim as my invention:

1. A drop hammer comprising a heavy drop body of heat treatable material having upper and lower end portions, at least the lower end portion having a plurality of sections therein defining walls in said body, said walls having a maximum thickness not exceeding the effective penetrating depth of a quenching liquid for effecting heat treatment of said sections.

2. A drop hammer as claimed in claim 1 wherein the upper end portion of said body includes a cavity adapted to receive a mass of relatively heavy material to increase the weight of said drop hammer.

3. A drop hammer as claimed in claim 1 wherein said heat treatable material is austenitic manganese steel.

4. A drop hammer as claimed in claim 3 wherein said maximum wall thickness is five inches.

5. A drop hammer as claimed in claim 3 wherein the walls are substantially uniform in section and said wall thickness is approximately 3½ to 4½ inches.

6. A drop hammer as claimed in claim 2 wherein said mass of relatively heavy material is lead.

7. A drop hammer comprising a heavy drop body of cast heat treatable material, said body including a plurality of concentric spaced tubular sections, a plurality of radially extending members interconnecting said tubular sections to define a plurality of passages in said body for circulation of a quenching liquid therethrough to effect heat treatment of the body and the tubular sections and radially extending members having a maximum thickness not exceeding the effective penetrating depth of quenching

liquid circulating between respective adjacent ones of said passages and between respective ones of said passages and the outer surface of the body.

5 8. A drop hammer as claimed in claim 7 wherein said heat treatable material is austenitic manganese steel and said sections and members are uniform in cross section.

9. A drop hammer as claimed in claim 8 wherein said tubular sections and radial members are approximately 3½ to 4½ inches thick.

10. A drop hammer comprising a heavy drop body of heat treatable material having upper and lower end portions, at least the lower end portion having a plurality of passages therein defining interconnecting walls in said body, and the walls between said passages and the outer surface of said body having a maximum thickness not exceeding the effective penetrating depth of a quenching liquid for heat treating said walls when circulated through said passages and about the outer surface of said body.

15 11. A drop hammer as claimed in claim 10 wherein said heat treatable material is austenitic manganese steel.

12. A drop hammer as claimed in claim 10 wherein the upper end portion of said body includes a cavity adapted to receive a mass of relatively heavy material to increase the weight of said drop hammer.

13. A drop hammer as claimed in claim 11 wherein the walls are substantially uniform in section and said wall thickness is approximately 3½ to 4½ inches.

14. A drop hammer comprising a heavy drop body including upper and lower end portions, the upper end portion of said body including a cavity adapted to receive a mass of relatively heavy material and means defining an opening at the upper end of said body for adding said mass to compensate for a loss weight due to wearing away of the lower end portion during use.
